Primary Examiner — Ramzi S Almatrahi(74) *Attorney, Agent, or Firm* — Volpe and Koenig, P.C.(57) **CLAIM**

The ornamental design for a monitoring camera, as shown and described.

DESCRIPTION

FIG. 1 is a perspective view of a monitoring camera in accordance with our design;

FIG. 2 is a top plan view thereof;

FIG. 3 is a right side elevational view thereof;

FIG. 4 is a left side elevational view thereof;

FIG. 5 is a front plan view thereof;

FIG. 6 is a rear elevational view thereof; and,

FIG. 7 is a bottom plan view thereof.

The broken lines represent unclaimed portions of the monitoring camera and do not form part of the claimed design. The dot-dash broken line defines the bounds of the claimed design and form no part thereof.

1 Claim, 4 Drawing Sheets(56)
